UNITED STATES PATENT OFFICE.

DAVID E. HUNTER, OF CAMBRIDGE, MASSACHUSETTS.

HOLDER FOR CARD-INDEXES.

SPECIFICATION forming part of Letters Patent No. 645,051, dated March 6, 1900.

Application filed November 30, 1896. Serial No. 613,887. (No model.)

To all whom it may concern:

Be it known that I, DAVID E. HUNTER, of Cambridge, county of Middlesex, State of Massachusetts, have invented an Improvement in Holders for Card-Indexes, of which the following description, in connection with the accompanying drawings, is a specification, like letters on the drawings representing like parts.

- 10 My invention relates to improvements in the holders or receptacles for card indexes or catalogues, and has particular reference to the provision of an expansible locking member for locking the cards in their receptacle.
- 15 It includes also means whereby the follower-block or back card-support is positively held on the locking member against movement in either direction and whereby said block is automatically engaged with said member and
- 20 yet will yield to permit sliding movement of the block along the locking member; and it further includes an improvement in the front and rear card supports or rests, whereby the tendency of the cards to climb up on said sup-
- 25 ports is counteracted.

Cards have been employed heretofore having open slots at their lower edges coöperating with a flattened lock-bar, the latter being turned on edge for the removal of the cards and being turned flatwise into loose engagement with the slot for the retention of the cards. This construction requires that the slot in the cards should have considerable depth in order that the rod may turn therein, thereby seriously cutting into the space of the card required for writing upon.

It is one object of my invention to provide an expansible or laterally-extensible rod, whereby shallow slots are sufficient in the cards, thereby economizing the space of the cards available for records, indexes, &c., my improved locking-rod being further capable of firmly engaging the cards, so as to hold them as definitely and tightly as desired.

45 Further purposes and advantages of my invention and the details thereof will be more definitely pointed out in the following description, and the invention will be further defined in the accompanying claims.

50 Referring to the drawings, Figure 1, in top plan, shows my invention applied in operative relation to an ordinary drawer and cards

therein. Fig. 2 is an enlarged detail, in vertical section, taken on line 2 2 of Fig. 1. Fig. 3 is an enlarged detail, in horizontal section, 55 being shown in position ready to be operated, the operation thereof being indicated in dotted lines. Fig. 4 is a sectional detail taken on line 4 4, Fig. 1. Fig. 5 shows in front elevation the escutcheon for the locking member. Fig. 6 is a sectional detail taken on line 6 6, Fig. 1. Fig. 7 is a top plan view, parts being broken away, showing another embodiment of my invention. 60

Reference-letter A designates a drawer or card-receptacle of any usual or preferred kind.

In the preferred embodiment of my invention I provide a compound locking-rod or a locking member B, made up of two rods b b', 70 connected together in parallel-ruler fashion and suitably pivoted to permit the rods b b' to swing together and apart. The locking member B is shown as centrally pivoted at either end on pivots b² b³, passed through the links b⁴ b⁵, the links consisting, preferably, of upper and lower plates, as shown in Figs. 2 and 3, and the rod b' being cut away at b⁶ to permit the rods b b' to be swung close together. A link b⁷ serves to strengthen the locking member between its ends. Preferably the rod b' is offset at b⁸, so as to extend forward at the middle of the drawer A, and is provided with a knob or finger-hold C. The latter is specially constructed to constitute a positive lock 85 for the locking member B, at the same time serving as the knob to pull out the drawer. The knob C is centrally recessed at c to receive a head b⁹ on the end of rod b'. The head is retained within the knob by means of a threaded socket or nipple c', tapped into the knob and secured by a pin c². The free end of the nipple c' is adapted to be screwed into a bushing D, fitted into the end of the drawer A and having a central aperture d to receive the rod b' and nipple c' when in locking position and a lateral recess d' to receive the rod b' when the locking member is in its contracted or collapsed condition. (Shown by dotted lines in Fig. 3.) An escutcheon E is 90 secured to the face of the drawer. Cards F, having elongated slots f, open at f' at their lower edges, coöperate with the locking member B. (See Fig. 4.)

The parts being as shown in full lines in Fig. 3, if it is desired to release the cards the knob C is pulled, thereby swinging the parts on the fixed pivot b^2 as a center, the locking member assuming its dotted position, Figs. 3 and 4, permitting any or all of the cards to be lifted from the drawer. If it is desired to secure the cards and lock the same, the knob is shoved in and screwed into position against the escutcheon, as shown in Fig. 2, rendering it impossible to move the locking member B in any manner.

A card-support or follower-block G of usual shape is provided at the rear of the cards and has a central aperture g to permit it to receive and to be slid along the rods b b' .

Loosely mounted on the rear side of block G, and preferably in a recess g' , (see Fig. 6,) is a clamp g^2 , shown as a spring loosely encircling a set-screw g^3 and frictionally engaged with rod b by means of its oppositely-concaved free ends g^4 g^4 . As the rod b is moved over into its dotted position, Fig. 3, the clamp g^2 slides over with it, and as the block G is shoved forward or back the clamp g^2 goes with it, having sufficient frictional grip on the rod b , however, to positively hold the block against being moved by the usual fingering of the cards.

The front lower edge of block G and the rear lower edge of the block H are cut off, as indicated at h . I have found that this effectively prevents the very objectionable tendency of the end cards to creep up on the face of the end supporting-blocks H and G.

As heretofore constructed the blocks H and G have sloped downwardly to a sharp edge, against which the adjacent cards would wedge and gradually creep up, so that when subsequently turned back or forward for inspection the slots f or other openings or perforations would be torn out. By the provision of the undercut or retreating lower edges h the cards are kept down in proper position without any tendency to creep or work up.

Referring to Fig. 7, it will be seen that instead of pivotally mounting and connecting the rods b b' I have secured cam-plates b^{10} to the rod b , the two rods b b' being longitudinally movable relatively to the drawer and the follower G having a rigid stop g^5 midway in the aperture g . The cam-plates b^{10} have inclined slots b^{11} therein, in which pins b^{12} on the rod b' are free to travel. It is obvious that as the rod b' is pulled it will slide along the slots b^{11} until it is moved inwardly against the stop g^5 , and further movement of the rod b' will then pull the rod b over against the stop g^5 , thus contracting the locking member B to its dotted position, Fig. 4.

Further detailed description of the operation of my invention is deemed unnecessary.

It will be apparent that the slots f in the cards need be only wide enough vertically to receive the slender rods b and b' , as shown in Fig. 4, and that the slots may be close to the lower edges of the cards, my object being to

save the valuable space of the body of the card for its primary use—viz., for entering records, &c., upon—the large and deep slots hitherto necessary having seriously encroached upon the writing-space of the cards.

My invention provides a locking member which simply expands to fill the slot without being rotated and without requiring any extra space in which to be moved, and by varying the length of the nipple c or the depth of the recess c the extent to which the rods b b' are separated may be varied, so as to engage the slots f as tightly or loosely as may be desired.

As the locking member B is simply expandable and does not turn, there is no tendency to wear off and break down the corners of the slots f adjacent the openings f .

Not only does the clamp g^2 hold the block G positively against movement in either direction, but it also holds the block automatically wherever placed and yet yields instantly to permit the block to be shoved along the rods when desired.

I do not restrict my invention to the details of construction shown, inasmuch as many changes in form, proportions, and arrangement may be resort to without departing from the spirit and scope of my invention.

Having described my invention, what I claim, and desire to secure by Letters Patent, is—

1. A card-holder for receiving therein cards having apertures, and a locking-rod for entering the apertures, said rod being movable longitudinally and laterally in the apertures.

2. A card-holder for receiving therein cards having apertures, and a pair of locking-rods for entering the apertures, one of the rods being movable longitudinally and being also movable laterally toward and away from the other rod.

3. The combination with a card-holder, of a laterally and longitudinally movable rod adapted to lock the cards therein, and means to move said rod laterally by its movement longitudinally.

4. The combination with a card-holder, of a longitudinally-movable locking member adapted to lock the cards therein, said locking member presenting a less-effective width in one position than it does in another position, and means to move said locking member longitudinally, said locking member being shifted from one to the other of its said positions by said longitudinal movement.

5. The combination with a card-holder, of a locking member for card-indexes, comprising two longitudinally-movable parts, connections between said parts permitting said parts to move toward and from each other, and means to move said parts.

6. The combination with a card-holder, of an expandable and longitudinally-movable locking member for card-indexes, means to expand the same, and means to lock said member in expanded position.

7. A card-holder for receiving therein cards

having apertures, combined with a horizontally-pivoted link or plate, a pair of parallel rods pivoted to said plate, and means at one end of said card-holder for turning said pivoted plate, thereby causing the spreading or bringing together of the parallel rods.

8. A card-holder, combined with a locking member for the cards, comprising a pair of parallel rods, and means for spreading and contracting said rods, said means including a link or plate centrally pivoted in the holder and connected at opposite sides of its pivot with said two rods, the turning of said plate on its pivot serving to spread or contract the rods.

9. In a card-holder, horizontally-pivoted plates at the front and rear of the holder, a pair of parallel rods pivoted to said plates, and means at the front of the holder for turning the front pivoted plate.

10. The combination with a card-holder, of a movable locking member, an aperture in the end of said holder, and a knob loosely connected with said locking member and adapted to be interlocked with said aperture, when interlocked said knob maintaining said locking member in fixed locking position.

11. The combination with a card-holder, of a movable locking member, an aperture in the end of said holder, and a knob having

limited longitudinal movement on the said locking member, and means to lock said knob in said aperture.

12. The combination with a card-holder, and locking member therefor, of a follower-block, 35 and a spring-clamp mounted on said block and having coöperating opposite spring-jaws to engage said locking member.

13. The combination with a card-holder, and a laterally-movable locking member therefor, 40 of a follower-block, and a clamp movably mounted on said block and engaging said locking member, said clamp being freely movable laterally with the locking member relatively to the block and holding said block 45 against longitudinal movement on said locking member.

14. In a card-holder, an end supporting-block for the cards, having a sloping face, said sloping face being cut away adjacent its 50 lower edge or provided with an undercut portion.

In testimony whereof I have signed my name to this specification in the presence of two subscribing witnesses.

DAVID E. HUNTER.
